UNITED STATES PATENT OFFICE

AUGUST WESTENDORF, OF BUFFALO, IOWA.

BUILDING CONSTRUCTION.

1,038,467.

Specification of Letters Patent. Patented Sept. 10, 1912.

Application filed November 13, 1911. Serial No. 659,958.

To all whom it may concern:

Be it known that I, AUGUST WESTENDORF, a citizen of the United States, residing at Buffalo, in the county of Scott and State of Iowa, have invented certain new and useful Improvements in Building Construction, of which the following is a specification, reference being had therein to the accompanying drawing.

- 10 This invention relates to silos and building blocks therefor, and has for its object the production of means for facilitating the securing of said blocks in an assembled position.
- 15 Another object of this invention is the production of an efficient door jamb for a silo or other building.

With these and other objects in view this invention consists of certain novel constructions, combinations and arrangements of parts as will be hereinafter fully described and claimed.

- 20 In the drawings: Figure 1 is a vertical section taken through the silo. Fig. 2 is a front view of a portion of the door jamb. Fig. 3 is a detail perspective of a portion of the door jamb and silo therefor. Fig. 4 is a central transverse section through the door sill. Fig. 5 is a fragmentary section 25 through one of the side blocks of the door sill. Fig. 6 is a detail perspective of one of the cornice blocks. Fig. 7 is a detail perspective partly in section of one of the construction blocks for the side of the silo. Fig. 8 is a detail perspective partly in section of a modified form of block which may 30 be used in connection with the construction of the silo. Fig. 9 is a detail perspective of a modified form of one of the end blocks for 35 the door sill before the opening for the reinforcing wire has been cut therethrough. Fig. 10 is a detail perspective view of a portion of the block disclosed in Fig. 9 showing the same cut away to permit the reinforcing rod to pass therethrough.

The silo is constructed of a plurality of hollow blocks 1 which are formed from vitrified shale clay. These blocks are provided upon their upper surfaces with longitudinally extending grooves 2 in which grooves are adapted to fit longitudinally extending reinforcing tie wires or rods 3. The blocks may be provided with only one groove 2 or may be provided with a plurality of grooves 50 to suit the fancy of the builder as illustrated

in Fig. 3 of the drawing. The ends of these tie wires or rods 3 engage vertically extending reinforcing rods 4 as clearly illustrated in Fig. 3 of the drawing. The usual cement or other substance may be used between the blocks for holding the same in a congested mass thereby firmly holding the reinforcing ribs or wires 3 in position within the groove 2. The rods 4 are placed within the door jamb or hollow block containing the same and extend centrally thereof and by having these blocks filled with cement or other similar material the rod will be greatly reinforced by being held within a practically solid body. The side blocks 65 constituting the door jamb are divided into two compartments, the rear compartment of which receives the reinforcing rod 4 above mentioned. The base side block 5 is provided with an off-set end 6 having an opening 7 formed therein. This opening 7 receives the ends of the sill block 8 which block is provided with openings 9 upon the upper surface thereof so as to allow the cement or other similar material to be poured 80 therein for constituting a substantially solid body. Rods 10 extend longitudinally of the sill block 8, and have their respective ends secured to the respective vertically extending rods, thereby firmly tying the base end blocks 85 5 in an assembled position relative to the sill block 8. Two of these rods 10 are preferably used, one of the same extending through each of the compartments of the sill block. Of course, the partition 11 formed centrally of 90 the sill block 8 is also provided with an opening 12 for allowing the cement or similar material to pass from one partition to the other. When the base end blocks 5 are also filled with cement, it will be obvious 95 that a substantially integral structure will have been formed between the end blocks and the sill block. The sides of the door jamb are formed of blocks 13 similar in construction to the base end blocks 5 and 100 these blocks 13 are provided with vertically extending grooves 14 for allowing the blocks to be easily placed over the vertically extending rods 4 thereby doing away with the necessity of placing each of the blocks over 105 the upper end of the vertically extending rods.

From the foregoing description it will be obvious that the entire construction of the silo will be firmly and rigidly tied together 110

through the combined use of the cement and tie rods above described.

Of course, the several blocks used in the construction of the silo may be formed in accordance with the building which is desired to be constructed. In the present instance, however, the blocks are slightly curved as illustrated in the drawing to conform to a substantially circular building.

10 A row of cornice blocks 15 are placed upon the top of the building and these blocks comprise three compartments 16 the rear compartment of which is preferably of the same width as the building blocks out of 15 which the silo is constructed. The other two compartments extend or project in front of the building as illustrated in Fig. 1. The top of the front compartment 16 slopes from its outer edge toward the top of the outer 20 compartment 16, thereby forming a gutter for allowing the drainage of the roof to be carried off to the desired point. The roof 17 is, of course, placed upon the cornice blocks 15. The cornice block is provided 25 upon the top thereof with a beveled wall 18 which prevents the water draining from the roof from falling over the side of the silo. The drain pipe 19 passes through the central 30 compartment of the cornice block and communicates with the upper surface thereof for carrying off the drainage from said cornice block.

From the foregoing description, it will be obvious that a very efficient cornice block 35 has been produced which will prevent the drainage from the roof from leaking over the side edges of the silo and will also readily carry the water from the roof to any desired point. It will further be obvious upon 40 giving Fig. 3 of the drawing careful consideration that by having the tie blocks provided with an off-set portion as previously described, a pocket has been formed for the reception of the sill block 9, as well as the 45 usual jamb constructed for the door which may be used in connection therewith.

Having thus described the invention what is claimed is:

1. In a building composed of blocks laid 50 in courses, the courses being interrupted to form a doorway, reinforcing means for holding said blocks in alinement, vertically extending rods, hollow base side blocks posi-

tioned about the base of said vertically extending rods, said blocks being provided with an off-set portion, an elongated hollow sill block having its ends seated in the off-set portion of said base side blocks, and means passing through said hollow sill block and engaging said vertically extending rods 55 for holding said rods together and also holding said side blocks in engagement with the ends of said sill block.

2. In a building composed of blocks laid in courses, the courses being interrupted to 60 form a doorway, reinforcing means for holding said blocks in alinement, vertically extending rods, a series of hollow side blocks positioned around said vertically extending rods and constituting a door jamb, 65 each of said blocks being provided with an offset portion for forming an abutting flange for the door adapted to be supported thereby, each of said blocks being provided upon one side with a vertically extending opening for facilitating the placing of said block around said vertically extending rods, a sill block positioned between two of the lower of said blocks, and means for tying 70 said rods and blocks in engagement with said sill block.

3. A door sill and jamb comprising a plurality of side blocks having openings formed therein, vertically extending rods, said side blocks placed around said rods, a 75 hollow sill block comprising an elongated body and having apertures formed therein, said hollow sill block being provided with a partition extending longitudinally thereof for constituting a plurality of compartments, 80 said partition having apertures formed therein, and said sill block being adapted to receive cement for forming a substantially solid body, and means passing through each of said compartments formed in said sill block and engaging said vertically extending rods for tying said rods, said blocks, and sill block together whereby a substantially 85 solid structure may be produced.

In testimony whereof I hereunto affix my 90 signature in presence of two witnesses.

AUGUST WESTENDORF.
